UNITED STATES PATENT OFFICE.

LUTHER C. CROWELL, OF BROOKLYN, NEW YORK.

WEB-FEEDING MECHANISM FOR PRINTING-MACHINES.

SPECIFICATION forming part of Letters Patent No. 365,051, dated June 21, 1887.

Application filed April 6, 1885. Serial No. 161,266. (No model.)

To all whom it may concern:

Be it known that I, LUTHER C. CROWELL, a citizen of the United States, residing at Brooklyn, county of Kings, and State of New York, have invented certain new and useful Improvements in Web-Feeding Mechanisms for Printing-Machines, fully described and represented in the following specification and the accompanying drawings, forming a part of the same.

Practical embodiments of this invention are illustrated in the accompanying drawings, wherein—

Figure 1 represents an end elevation of a rolled web of paper with this improved controlling and delivering mechanism applied thereto. Fig. 2 is a plan or top view of the same. Fig. 3 is an end elevation of the driving-pulley and its actuating clutching mechanism. Fig. 4 is a plan view of the same, the shell of the pulley being in part removed to expose the interior. Fig. 5 is a transverse sectional elevation taken on the line x of Fig. 4. Fig. 6 is an end elevation, and Fig. 7 a side elevation, of a modified arrangement of the apparatus. Fig. 8 is a transverse sectional elevation of a modification of the clutch; and Figs. 9 and 10 are views similar to Fig. 1, illustrating modifications of the controlling mechanism, hereinafter referred to.

It is the primary object of this invention to provide a rolled web of paper which is to constantly decrease in size as the web composing it is fed to a printing-machine or other apparatus operating upon such web, with a delivering and controlling mechanism, by the operation of which said rolled web shall be moved at a surface speed suited to that of the machine operating upon it during the starting, running, and stopping of such machine.

Another object to be attained by a modified structure is an operation of the controlling and delivering mechanism, whereby said web shall be driven at a surface speed suited to that of the machine operating upon it during the starting and stopping of such machine, and which, when such machine reaches a high or a running speed, will apply an appropriate controlling-friction to said web.

In all machines in which a rolled web is fed by being unrolled, and especially in such as

operate at high speed, and thus through their rapid consumption of the web require the roll of web to be of large size and consequent weight, there is great liability that the web will break or tear as the machine begins its movement, for the reason that, no matter how slowly that movement is begun and increased, the means for overcoming the inertia of the roll (being a thin paper web) is too frail to be subjected to the strain imposed, and when the machine attains its high or running speed and the roll revolves with great rapidity it has a tendency to gather speed and feed off the web too rapidly, thus destroying the tension necessary to accomplish its smooth and even feeding movement; and, further, when the machine stops the speed theretofore attained by the roll will cause a quantity of the web to be unrolled, which web is not carried into the machine, but forms a slack, that requires to be taken up. As a means for controlling the rotation of the rolled web, and therefore the speed at which it is unrolled, and at the same time apply a proper tension to that portion of the web extending from the roll to the devices operating upon it, a friction device has been applied to the shaft of the rolled web; but practically this friction device requires constant attention and constant change to secure the best results. It may be also remarked that the application of a positive driving mechanism to a rolled web (such, for instance, as that used in paper-damping machines) is impractical when used in connection with a web-printing machine for the purpose of feeding and controlling the movement of the rolled web, for the reason that the speed of such driving mechanism, if in the least degree greater or less than that of the printing-machine, will result in feeding the web too fast or too slow, causing slack or a breaking strain. This will be apparent when it is considered that the webs are of great length and that the impression-cylinders of the printing-machines are covered with a yielding blanket subject to varying degrees of compression to impart the degree of impression suited to webs of different qualities, and results in making the surface speed thereof a varying one, which cannot be compensated for in the positive driving mechanism of the rolled web.

The present improvements not only avoid these defects, but provide automatic means to accomplish a perfect feeding and controlling movement of the roll of web at all times, 5 whether the machine is stopping, starting, or running.

These improvements consist in a moving roller or belt arranged to travel in contact with the roll and follow its periphery as it decreases in size, which roller or belt is provided with a driver that runs said belt at a speed appropriate to that of the machine to which the web is being fed. It also consists in combining with said roller or belt a means for disconnecting or throwing out of action its driving means, so that the turning roll may become the driver, and thus have the friction of the roller or belt applied to it.

It also includes a clutching mechanism operating by centrifugal force to cause the roller or belt to be driven by the machine to which the web is being fed when said machine runs slowly, and to be driven by the roll, and thus apply friction to it when the said machine runs 25 at a considerable speed.

Other features of the invention, including particular combinations and constructions, are embraced herein, all of the same being fully hereinafter set forth and claimed.

To enable these improvements to be readily understood, it may first be stated that, although no machine for operating upon the web itself is shown, it is to be understood that the web 100 from the rolled web 200 is led to a machine 35 which performs some operation upon it, and thus consumes the web.

While there are many other machines to which this improved apparatus is applicable, it is more practically suited to printing and 40 like machines which are rotative in character and when running constantly draw upon the web and cause it to feed progressively onward.

As will readily be apparent, it becomes a 45 difficult matter when the rolled web is large and heavy for the machine operating upon the web, and which imparts to it a positive draft, to overcome the inertia of said roll and properly unwind the web at a speed equal to the 50 surface movement of the mechanism to which it is delivered without frequently tearing or breaking the web, and that, in consequence of the high speed at which such machines run, it must follow that there will be a great tendency 55 for the heavy roll of web to gather speed, and thus give off or unwind its web too rapidly, thereby causing slack, which is injurious; and, further, that when the machine is to be stopped there will also be a tendency in the heavy roll, 60 due to its inertia, to come to a state of rest more slowly than does the mechanism to which it is delivered, thus acting to feed off a quantity of unused web, and thus produce a considerable slack, which, whether taken up 65 by turning the roll backward or left unrolled, aids in causing a tear or break upon restarting the machine, for the reason that a free

portion of the paper moves into the machine before any draft is made upon the roll, whereby the power of the machine is applied to the 70 roll after the web has attained some considerable speed. All of these defective operations, though in part provided against by the friction device commonly applied to the shaft of the rolled web, still exist when that appliance 75 is used, and more especially do they exist where in more modern printing-machines the web is not only passed between printing mechanisms, but is manipulated by web transferring and associating apparatuses. Another defect 80 of the friction-roll appliance spoken of is that unless constantly changed by hand manipulation it remains a constant power, applying a friction not lessening, as it should, in proportion as the roll decreases in size, but, on the 85 contrary, increasing as the roll so decreases.

This improved delivering and controlling mechanism consists, primarily, of an endless belt, 20, running over a pulley, 30, and a roller, 40. The pulley 30 is hung on a shaft, 50, that receives motion through a toothed wheel, 60, from the machine with which this mechanism is connected. The roller or cylinder 40 is hung on an axle turning freely in a frame composed of arms 70 80, that swing 95 freely on shaft 50, said arms 70 80 thus constituting a swinging frame that bears the belt 20 constantly in contact with the rolled web 200, no matter what its proportions are or to what size it is reduced, as appears by the full and dotted lines in Fig. 1. The arms 70 80 are made adjustable longitudinally in boxes 71 72, wherein they are secured by set-screws.

As thus far described it will appear that if the pulley 30 is fast upon the shaft 50 and driven by the wheel 60 by gearing connected with a properly-timed driving-wheel of the machine operating upon the web of paper, the belt 20 will be moved with a surface speed equal to that of the said machine, and thus, 105 since the belt 20 constantly bears upon the rolled web of paper with a friction equal to its own weight, that of the roller 40, and the arms supporting it, a driving action upon the periphery of said rolled web will be effected, and hence the rolled web will be turned with a surface speed equal to that of the machine operating upon the web, and thereby cause the web to be fed evenly and truly to that machine; but while this is true theoretically, practically 115 it is best to so time the gearing that such feeding of the rolled web shall be very slightly less than the speed of the said machine, so that the belt 20 while operating as a driver shall apply a slight frictional drag to the rolled web. The connection between the pulley 30 and the shaft 50 is, however, made through a frictional clutch, the purpose of which is to enable the driving action of the machine imparted through said shaft 50 to be suspended 120 when a high or running speed of the machine is attained, and to be reapplied when such speed is modified. For this purpose any means of operating said clutch may be adopted and 125 130

the structure of the clutch may be modified to suit the requirements of such operating means and adapted for co-operation therewith. A means for coupling said shaft 50 with a driver 5 of the printing or other machine and uncoupling the same may be applied when the pulley 30 is fast upon the shaft 50 to the shaft itself. Thus a frictional clutch operating to set that shaft in motion would accomplish the result, 10 or any other devices by which the driving-gears may control the motion of the shaft more or less positively might be applied. In the mechanism as here illustrated, however, a friction-clutch operated by centrifugal force 15 is adopted as one of the best means for accomplishing this result. This clutch is shown best in Figs. 3, 4, and 5, and consists of shoes 31, adapted to bear against the inner periphery of the pulley 30, which shoes are pivoted at 20 the ends of levers 32, that are fulcrumed to arms 33 fast on the shaft 50. The levers 32 have weighted ends 34, which are tied to said arms 33 by means of pivoted rods 35, which pass through the weighted ends 34 of the 25 levers, and are connected to said levers by means of a spring, 36, coiled about them to bear at one end upon the bottom of a recess in the weighted ends 34, and at the other upon adjustable nuts screwed onto said rods. Normally 30 these springs have a power (which may be varied by turning said nuts) that will hold the levers 32 in such a position as to apply the shoes 31 to the periphery of the pulley 30 with a force sufficient to lock said pulley to the shaft 35 50 and cause the same to partake of the movements of that shaft. When, however, said shaft rotates the pulley with a speed sufficient to cause centrifugal force to move said levers in a direction opposite to the force applied by the 40 springs, and thus compress said springs and move the levers sufficiently to withdraw the shoes from contact with the periphery of the pulley, said pulley will not be driven by the shaft, though the parts of the clutch carried 45 by the shaft will continue to rotate therewith. (See Fig. 3.) When the pulley is clutched to the shaft 50, it will of course be moved with the speed of the printing or other machine, and hence drive the belt 20 with a like speed, 50 and therefore move the rolled web with a like speed, the result of which is that when the machine slowly starts, this controlling delivering mechanism, having a like motion, slowly unrolls the web and positively feeds the same 55 into the printing or other machine with a speed equal to that of said machine, and hence relieves the web from any undue draft upon it, or from receiving any sudden jerk which would result if the printing or other machine were 60 required to impart motion to the roll through the web of paper, and thus overcome the inertia due to the weight of the roll by a draft upon the web itself. When, however, the speed of the pulley 30, and consequently that 65 of the web, has reached the running speed of the printing-machine, and that speed is great enough to release the clutch through

the centrifugal action of the weighted arms 34, the pulley 30 will no longer be driven directly from the printing-machine, but must thereafter be moved by the frictional contact of its belt 20 from the rolled web of paper. From this it results that, since the said rolled web, now propelled by the draft upon itself, is caused to drive the belt 20, such belt will apply a certain amount of friction thereto, and thus operate as a drag sufficient to produce a friction that will impart to the web a proper tension to cause its even and regular delivery into the printing-machine. This friction, which is largely due to the weight of the arms 70 75 80 85 90 95 100 105 110 115 120 125 130 135 140 145 150 155 160 165 170 175 180 185 190 195 200 205 210 215 220 225 230 235 240 245 iently and quickly mounted in the machine, that the apparatus be located at the side of the rolled web, and for this purpose there is shown in Figs. 6 and 7 an arrangement thereof suited to such position. The construction of this controlling and delivering apparatus differs from that just described only in the means for causing the vibrating frame to move and maintain the belt 20 constantly in contact with the periphery of the rolled web. In the former apparatus this is accomplished by its own gravity. In this modification it is accomplished by means of a weight, 300, the power of which is applied through a lever, 41, fast upon a shaft, 51, by a set screw, which shaft has an arm, 47, that is connected by a link, 42, pivoted to a bar, 43, that is attached to the rear of the levers 70 80. As is obvious, this weight 300 will constantly apply a power to said arms, and through them cause the belt 20 to constantly follow the periphery of the roll 200 as the latter decreases in size. It may now be observed that this same structure can be applied to the apparatus shown in Figs. 1 to 5, the only thing necessary being to apply the power of the weight through a cord-and-pulley attachment connected with the lever 41, or by a suitable arrangement of levers; and, again, if it be desired that the frictional pressure of the belt 20 shall be adjustable, that may be accomplished by varying the position of the weight on the lever.

It will be apparent that the separation of the clutch from the driving pulley may be regulated with respect to the speed of the machine by adjusting the power of the springs 36 on the rods 35, so that the velocity of the shaft 50, required to withdraw the shoes 31 from the periphery of the pulley 30, may be predetermined to suit the requirements of the machine operating upon the web.

It will further be observed that when the rolled web is large and requires the greatest friction a larger part of the belt 20 bears upon its surface than is the case when the roll is small and requires a less degree of friction, the size of the roll and its frictional requirements being thus in a degree adjusted by its decreasing size. This frictional pressure may, however, be a constantly-changing quantity if the weight of the lever 41 is arranged to move more and more away from the fulcrum as the roll decreases. It is, however, obvious that a simple friction may be constantly applied between the shaft 50 and the belt-pulley 30 without departing from the features of this invention, the friction being such that under ordinary circumstances it will be sufficient to control the movement of the web, but will allow the pulley to slip before the difference in speed between the pulley and the printing-machine will cause a breaking strain upon the web. This may be accomplished in the device illustrated by securing the levers 32 in a fixed position, so as to apply the proper degree of friction between their shoes 31 and the pulley 30.

In Fig. 8 I have illustrated a mode of con-

necting the weighted lever-arms together, so that when one moves the other will also move. This arrangement prevents any improper operation which might result from the action of gravity. This is accomplished by connecting the weighted end of one lever to the end of the other lever by spring seated rods 35, whereby any movement of one lever will be transmitted to the other.

If a laterally-running clutch is arranged to slide on the shaft 50, it is obvious that a single spring may be used in connection with two or more weighted toggle-levers, having a bearing at one end against a collar on the shaft and attached at the other to the sliding part of the clutch, the spring acting to apply the clutch, as before explained, and the weighted levers to move outwardly by centrifugal force in the manner of a governor, to cause the unclutching action.

Although the belt 20 is especially advantageous, for the reason that it will have contact with a large portion of the periphery of the rolled web, it is obvious that the belt 20 may be omitted and the roller or cylinder 40 be made the element in contact with said roll, as is shown in Figs. 9 and 10. In that case any mode of gearing it to the pulley 30 may be adopted—as, for instance, by a belt, 80, extending from said pulley over a similar pulley, 81, secured on the end of the shaft carrying the roller 40, as in Fig. 9, or by means of the gearing shown in Fig. 10, in which case the pulleys 30 and 81 are substituted by gears 30^a and 81^a, similarly mounted, and connected by intermediates 82, mounted on the side of one of arms 70, as will be readily understood; and while an endless moving belt enters specifically as an element in the claims, it is to be understood that in the sense in which it is used it is intended to be an equivalent for the roll here described.

From the foregoing it will be seen that the essential characteristic of this invention is the driving of a rolled web at a speed sufficiently less than that of the machine which operates upon it so that a suitable tension is created, while the driving means is not so positive as to cause a breaking strain upon the web.

What is claimed is—

1. In a web-controlling device, the combination, with a continuously-moving endless belt adapted to rest frictionally upon a rolled web, of means, substantially as described, for actuating said belt to control the unwinding speed of said rolled web, substantially as described.
2. In a web-controlling device, the combination, with an endless belt adapted to rest frictionally upon a rolled web, of means, substantially as described, for actuating the belt, whereby the rolled web at times is driven by said belt, and vice versa, to regulate the unwinding speed of the rolled web, substantially as described.
3. In a web-controlling device, the combination, with an endless moving belt adapted

to rest frictionally upon a rolled web to control its unwinding speed, of a driver for actuating the same, and means, substantially as described, operating automatically to put the 5 driver out of action, substantially as described.

4. In a web-controlling device, the combination, with an endless moving belt suitably mounted upon rollers and adapted to rest frictionally upon a rolled web to control its 10 unwinding speed, of a driven shaft, upon which one of said rollers is mounted for actuating the belt, and means, substantially as described, operating automatically to put the driven shaft out of action, substantially as 15 described.

5. In a web-controlling device, the combination, with an endless moving belt carried by a roller hung in a swinging frame and mounted so as to rest frictionally upon a rolled web to 20 control its unwinding speed, of a driver for actuating the same, and means, substantially as described, operating automatically to put the driver out of action, substantially as described.

25 6. In a web-controlling device, the combination, with an endless belt carried by a roller hung in a longitudinally-adjustable frame and mounted so as to rest frictionally upon a rolled web to control its unwinding speed, of a driver, and 30 connections between it and the belt for actuating the latter, substantially as described.

7. In a web-controlling device, the combination, with an endless moving belt carried by a roller hung in a swinging frame and mounted 35 so as to rest frictionally upon a rolled web to control its unwinding speed, of a driver, and connections between it and the belt for actuating the latter, and a weighted lever for moving said frame to hold the belt in contact with 40 the rolled web, substantially as described.

8. In a web-controlling device, the combination, with a traveling belt mounted so as to rest frictionally upon a rolled web to control its unwinding speed, of a driver, and connections 45 between it and the belt, substantially as described, to drive the belt or be driven thereby, substantially as described.

9. In a web-controlling device, the combination, with an endless traveling belt resting 50 upon a rolled web, of a driver for moving said belt, and a clutch interposed between said belt and the driver, substantially as described.

55 10. The combination, with an endless traveling belt mounted so as to bear upon a rolled web, of a pulley for driving said belt, and a clutch interposed between said pulley or its

shaft and the driver, substantially as described.

11. The combination, with an endless moving belt held continuously in contact with a rolled web, of a pulley for driving the belt and a friction-clutch for connecting said pulley with the shaft of the driver, constructed to operate by centrifugal force to unclutch said 60 pulley according to the speed attained, substantially as described.

12. The combination, with the belt 20, hung in a moving frame so as to rest upon a rolled web, of a driving-pulley, as 30, driving-shaft 70 50, and a clutch interposed between said shaft and pulley, substantially as described.

13. The combination, with the belt 20, hung in a moving-frame, of a driving-pulley, as 30, driving-shaft 75 50, a clutch interposed between said shaft and pulley, and a weighted lever, as 41, for moving said swinging frame and holding the belt in contact with a rolled web, substantially as described.

14. The combination, with a friction-clutch 80 consisting of pivoted swinging levers 32, carrying at one end a brake-shoe, 31, and having their opposite ends weighted, of a driving-pulley, as 30, the belt 20, hung in a moving frame and arranged to run in contact with a 85 rolled web, and a driving-shaft, 50, substantially as described.

15. The combination, with a friction-clutch consisting of pivoted levers 32, each carrying a friction-shoe, 31, at one end and having 90 their opposite ends weighted, and provided with tie-rods 35 and springs 36, of a driving-pulley, as 30, the belt 20, hung in a moving frame and arranged to run in contact with a rolled web, and a driving-shaft, 50, substantially as described.

16. The combination, with a friction-clutch consisting of pivoted levers 32, each carrying a friction-shoe, 31, at one end and having 100 their opposite ends weighted, and provided with tie-rods 35 and springs 36, and means for adjusting the power of said springs, of a driving-pulley, as 30, the belt 20, hung in a moving frame and arranged to run in contact with a rolled web, and a driving-shaft, 50, substantially as described.

In testimony whereof I have hereunto set my hand in the presence of two subscribing witnesses.

LUTHER C. CROWELL.

Witnesses:

T. H. PALMER,
GEO. H. GRAHAM.
